UNITED STATES PATENT OFFICE.

MARTIN R. HACKERSON, OF DENVER, COLORADO.

MUSIC-STAND.

No. 870,529.

Specification of Letters Patent.

Patented Nov. 5, 1907.

Application filed October 3, 1906. Serial No. 337,239.

To all whom it may concern:

Be it known that I, MARTIN R. HACKERSON, a citizen of the United States of America, residing at Denver, in the county of Denver and State of Colorado, have invented certain new and useful Improvements in Music-Stands, of which the following is a specification.

My invention relates to improvements in music stands such as used in orchestras and in general by 10 players of orchestral or band instruments.

The object of the invention is to provide the upper portion or desk of the stand, which in practice supports the music book or sheet, with an appliance capable of mechanically measuring the time or rate of movement of a musical composition by progressively indicating at a rate of speed in conformity with the rhythm or movement of the piece, the various notes arranged on the sheet of music deposited on the stand. The indicating means on one stand may be operated independently or the various music stands employed in an orchestra may be connected so that their respective indicators will move in unison, being actuated by a mechanism in one of the stands, preferably the one employed by the leader or director.

I attain these objects by the mechanism illustrated in the accompanying drawings, in the various views of which like parts are similarly designated and in which,

Figure 1—represents a fragmentary plan view of the normally sloping top portion or desk of the stand, Fig. 2—a longitudinal section taken along a line 2—2, Fig. 1, Figs. 3 and 4—enlarged side elevations of the contrivance on the indicator carrier employed to engage the endless screw, showing two positions, Fig. 5—an enlarged cross section along a line 5—5, Fig. 1, Fig. 6—an enlarged fragmentary view of a portion of the casing showing the extremity of the speed regulating lever, Fig. 7—a plan view of the normally sloping top or desk of the stand having a sheet of music in operative position, Fig. 8—a fragmentary cross section of the stand in the normal or operative position, Fig. 9—a fragmentary section similar to the one illustrated in Fig. 2 showing a modification of the mechanism which adapts it to actuate a plurality of subordinate stands, Fig. 10—a plan view of one of the subordinate stands and Fig. 11—a bird's-eye view of a plurality of stands, interconnected to operate in unison.

In the drawings 6 indicates the in practice sloping top or desk portion of the stand and 7 the standard connecting it with the base or foot, which for obvious reasons is omitted from the drawings. Desk 6 is composed of a rectangular oblong box 8 which contains the mechanism designed to actuate the indicator, and the either integral or detachable, downwardly ranging 55 flat portion 9 which extends from the lower side of the box in a plane with its uppermost edges. A rest 10

along the lower edge of the extension 9 provides a support for the book or sheet of music placed on the stand as illustrated in Fig. 7.

11 indicates the indicator-carrier composed of the 60 parallel bars 12, which in practice extend transversely of the desk and the cross pieces 13 and 13^a, the upper and lower ones (13) of which are respectively disposed above the upper side of box 8 and below the outer edge of the extension 9. The extremities of the cross 65 bars 13 are bent upwardly to provide uprights 14, upon the upper ends of which the indicator wires 15 are stretched in parallel relation to the longitudinal bars 12 of the carrier. The body portion of the carrier is disposed below the upper surface of the desk through 70 longitudinal slots 16 in the sides of box 8 while the indicator wires 15 extend above the said surface and the thereupon deposited book or sheet of music. Carrier 11 has a lateral reciprocating movement through 75 slots 16, along two parallel guide rods 17 which are secured within the box, the said movement being imparted thereto by the spring-actuated mechanism 18 situated on the right end of the box and which will now be described.

19 indicates a coiled spring, one end of which is secured to an upright spindle 20, rotatably mounted between the bottom portion of the box and a therewith parallel plate 21, while its opposite extremity is fastened to a suitable fixed portion of the device. The rotary movement imparted by spring 19 when unwinding, to the spindle 20 is transmitted through instrumentality of a train of gears 22, to a horizontally disposed beveled gear wheel 23, into which meshes a corresponding pinion 24 at the outer extremity of an endless or feed screw 25. The latter being rotatably 90 supported in one of the ends of the box and the therewith parallel partitions 26 and 26^a, extends subjacent the carrier and the guide rods 17 in parallel relation thereto and has a plain portion 25^a upon which is mounted a governor 27 of conventional construction. 95

The sliding sleeve 28 of the governor which is connected with the balls 29 by the links 30 engages the upwardly extending bifurcated extremity 31^a of a lever 31 which being disposed transversely along the bottom of the box, is fulcrumed thereon by means of 100 a pin 32. The extremity of the outer arm of lever 31 is pivotally connected with a rod 33 which being provided with a series of ratchet teeth, may be held in any desired position by engagement with a catch or dog 34, arranged to project into the interdental spaces. 105

Rod 33, extending parallelly to the side of box 8, projects through an aperture 35 in one of its ends, and is provided at its outer extremity with a handle 35^a to facilitate manipulation.

Carrier 11 is provided with a bell crank lever 36 pivoted to the outermost longitudinal bar 12 by means of a pin 37. The downwardly extending arm 36^a, of le-

ver 36, terminates within a short distance from the bottom of the box, while its other arm 36^a is provided with a downwardly ranging extension 38, the lower extremity of which is arcuated and constitutes a detent held normally in engagement with the thread of the endless screw 25, by a spring 39 which being secured upon the bar 12, bears upon the arm 36^a of the lever.

- A triangular stop 40 is secured upon the bottom portion of the box in the path of arm 36^a of the bell crank, so that when the carrier moving towards the left of the apparatus has completed its stroke, the extremity of the said arm will, by contact with the slanting edge of the stop, be impelled inwardly and in consequence 10 disengage the curved extremity of the extension 38 from the thread of the endless screw. When by contact with the stop 40, the lever 36 is forced out of engagement with the screw, it is prevented from resuming its original position during the return stroke of the 15 carrier after the arm 36^a has moved out of engagement with the stop, by a pawl 41, pivoted to the bar 12 at 42 and maintained in its normal upright position by a spring 44 and a stop 44^a. The curved portion of the 20 extremity 38 or detent is to this end provided with a nose 43, which when the arm is forced out of contact with the screw engages the hook shaped lower extremity of the pawl, as shown in Fig. 4, in which position it is maintained by pressure of the spring 44, until the 25 carrier has returned to its original position at the right hand end of the desk when the slanting edge of a stop 45 fixed on the box engages an extension 46 of the pawl, which projects beyond its fulcrum above the bar 12 and by forcing the lower extremity of the pawl rearwardly, releases the detent 36^a which, by action of the 30 spring, at once resumes its normal position in contact with the screw thread. When, by movement of the endless screw, the carrier moves towards the left of the device, it causes rotation of a spring roller 47, with which it is connected by means of cords 48, one extremity of which is wound around the roller while their other extremities are secured to one of the longitudinal bars 12. The rotary movement of the roller 47, which in construction is similar to the rollers commonly used on window shades, will cause the spring secured there- 35 40 45 50 55 60 65 70 75 80 85 90 95 100 consequence turns about its fulcrum and engages the pawl 41 as heretofore described, (see Fig. 4).

When the device is employed to actuate in addition to its own carrier, the carriers of a plurality of subordinate music stands, it is desirable that the extremities of the endless screw shaft be extended beyond the ends of the box, as shown in Fig. 9, for the purpose of operatively connecting the actuating mechanism with the adjacent stands, as illustrated in Fig. 11, which represents a diagrammatical bird's-eye view of a plurality of interconnected music stands.

Fig. 10 illustrates a plan view of one of the subordinate stands which in principle, operation and construction are identical with the principal stand, the actuating mechanism comprising the spring and gearing being omitted.

53 designates the box having the extension 54, 55 is the carrier with the indicator wires 56, 57 the spring roller connected with the carrier by cords 58, 59 the connecting lever, 60 and 61 respectively the stops employed to release the lever 59 and the pawl 62, and 63 the endless screw shaft, the extremities of which extend beyond the ends of the box.

The movement of the screw on the principal stand (designated by A in Fig. 11) may be transmitted from either end to the corresponding screws in the subordinate stands (marked B) by any of the many means adapted to this purpose. In the construction shown in the drawings, the object is accomplished by means of intermediate shafts or rods 52, interposed between the principal stand and the adjacent subordinate ones 95 and between each successive pair of intermediate stands.

The ends of rods 52 are flexibly connected with the protruding extremities of the endless screw shafts in the various stands, by means of universal joints 52^a, so that when by movement of the spring, the screw in the principal stand is rotated, the shafts on the other stands will synchronously rotate at a uniform rate of speed and the various indicator carriers will consequently move in unison from the right to the left.

In the operation of the device the mechanical construction of which is set forth in the preceding description, the score or notation of the musical compositions is especially arranged for the purpose as shown in Fig. 7 of the drawings in which the music is designated by the reference numeral 64. The bars 65 which separate the various notes comprised in the composition are equidistantly spaced along each staff 66, in alignment with those on the other staffs and the spaces thus obtained divided into two equal parts for half notes, four equal parts for quarter notes and so on. The mu-

sician, preparatory to playing a composition, arranges the sheet or book of music on the desk so that the aligned first bars at the left hand end of the staffs on the two pages are respectively in alignment with the two indicator wires, which as illustrated in Fig. 8,

posited thereon. The consecutive positions of the wires in alinement with the successive bars on each staff indicate to the musicians the exact period at which each note should be ended and the next one commenced, which not only assures their playing the piece in correct and even tempo but furthermore enables the various players in the orchestra to play in perfect unison and consequent harmony. When the wires have reached the last bars at the end of the staffs, the carriers automatically return them to the place of beginning by action of the above described releasing mechanism while in case the musician desires to repeat a portion of the music before the end of the staff is reached, he may return the carrier to its original position by manipulation of the crank 50.

The invention is particularly adapted for use in schools of music and amateur bands, as it enables the players to accurately follow the music and obviates the necessity of watching the movements of the leader 20 to learn the tempo in which the piece is to be played.

Having thus described my invention what I claim is:—

1. A music stand comprising in combination, a desk adapted to support a music sheet, a carrier intermediate 25 its ends having a reciprocating movement, and linear, indicatory members extending transversely of the desk above its supporting surface and connected at their extremities with the carrier.

2. A music stand comprising in combination a desk, 30 adapted to support a music sheet, an actuating mechanism, a reciprocating carrier normally at one end of the desk carrying indicatory members transversely of the desk and above its supporting surface, and having means to operatively connect with the said actuating means, means to automatically return the carrier to its normal position and an instrumentality adapted to break the connection between the said carrier and the actuating means.

3. A music stand comprising in combination a desk, adapted to support a music sheet, an actuating mechanism, a reciprocating carrier normally at one end of the desk carrying indicatory members transversely of the desk and above its supporting surface, and having means to operatively connect with the said actuating mechanism, means to automatically return the carrier to its normal position, and means to automatically break the connection between the actuating mechanism and the carrier when the latter has traveled a predetermined distance.

4. A music stand comprising in combination a desk, adapted to support a music sheet, an actuating mechanism, a reciprocating carrier normally at one end of the desk carrying indicatory members transversely of the desk and above its supporting surface, and having means to operatively connect with the said actuating mechanism, means to automatically return the carrier to its normal position, means to automatically break the connection between the actuating means and the carrier when the latter has traveled a predetermined distance, and automatic means to reestablish the said connection when the carrier reaches its normal position.

5. A music stand comprising in combination a desk, adapted to support a music sheet, a carrier normally at one end of the desk carrying indicatory members transversely thereof and above its supporting surface, an end-

less screw rotatably mounted on the desk, a motor to actuate the screw, a detent on the carrier arranged to operatively engage the screw, and means to automatically return the carrier to its normal position. 65

6. A music stand comprising in combination a desk, adapted to support a music sheet, a carrier normally at one end of the desk carrying indicatory members transversely thereof and above its supporting surface, an endless screw rotatably mounted on the desk, a motor to actuate the screw, a detent on the carrier arranged to operatively engage the screw, means to automatically return the carrier to its normal position, and a governor arranged to regulate 75 the rotational velocity of the screw.

7. A music stand comprising in combination with the music supporting desk, an endless screw rotatably mounted thereon, a motor to actuate the screw, a carrier having an indicatory member extending over the upper surface of 80 the desk, a detent on the said carrier arranged to normally engage the screw and automatic means to release the said detent at the end of the carrier's stroke.

8. A music stand comprising in combination with the desk, an endless screw rotatably mounted thereon, a motor to actuate the screw, a laterally movable carrier having an indicatory member extending over the upper surface of the desk, a detent on the said carrier normally engaging the screw, a tension device tending to retain the carrier in 85 its normal position, and means to release the detent when 90 the carrier has traveled a predetermined distance.

9. A music stand comprising in combination with the desk, an endless screw rotatably mounted thereon, a motor to actuate the screw, a laterally movable carrier having an indicatory member extending over the upper surface 95 of the desk, a detent on the said carrier normally engaging the screw, a tension device tending to retain the carrier in its normal position, means to release the detent at the termination of the carrier's travel, locking means to retain the detent in the released position, and means to cause its 100 reengagement when the carrier reaches its normal position.

10. A music stand comprising in combination with the desk, an endless screw rotatably mounted thereon, a motor to actuate the screw, a laterally movable carrier having an indicatory member extending over the upper surface of the desk, a detent on the said carrier normally engaging the screw, a tension device tending to retain the carrier in 105 the latter's normal position, and means to release the detent at an arbitrary point of the carrier's travel.

11. A music stand comprising in combination with the music supporting desk, a carrier having indicatory members extending above its upper surface, a mechanism adapted to impart a reciprocating movement to the said carrier and to be operatively connected with mechanisms of adjacent, similar stands, suitable means to make the 115 said connection, and a suitably located motor arranged to actuate the connected mechanisms.

12. A music-stand comprising in combination with the music-supporting desk, an endless screw rotatably mounted thereon, a carrier having indicatory members extending over the upper surface of the desk, operatively connected with the said screw, means to operatively connect the latter's extremities with screws of adjacent similar stands, and a suitably located motor arranged to rotate the connected screws. 120

In testimony whereof I have affixed my signature in presence of two witnesses.

MARTIN R. HACKERSON.
